UNITED STATES PATENT OFFICE

HENRY PERRY, OF LAKELAND, FLORIDA

DOORCHECK

Application filed December 1, 1928. Serial No. 323,014.

This invention relates to improvements in door checks or closers and relates particularly to improved means for mounting an air cushion check which will effectively prevent a door to which it is attached from closing violently and which will also permit the door to be opened to its fullest extent.

The present invention contemplates the provision of a cylinder pivotally mounted at one end upon a door at the top and adjacent the free side edge thereof and carrying a piston pivotally connected to an arm which is in turn pivotally attached to the under side of the door frame at the top. Means is associated with the arm whereby its movement will be retarded so that when the door is open the piston will first be drawn from its cylinder after which a pull will be exerted upon the arm which will swing outwardly with the door thus allowing the door to swing back to an open position in a plane substantially parallel to the face of the frame in which the door is mounted. Upon the door being released the pivoted arm is first forced inwardly beneath a resilient retarding friction plate and after the arm has come to a stop the piston is forced into the cylinder, compressing air therein which slowly escapes from the inner end of the same.

The invention will be best understood from a consideration of the following detailed description taken in connection with the accompanying drawing forming a part of this specification, with the understanding, however, that the invention is not confined to a strict conformity with the showing of the drawings but may be changed or modified so long as such changes or modifications mark no material departure from the salient features of the invention as expressed in the appended claims.

In the drawings:—

Figure 1 is a transverse sectional view through the front portion of a door and the frame, the section being taken substantially upon the line 1—1 of Figure 2, showing the device embodying the present invention applied thereto;

Figure 2 is an elevational view of the upper portion of the door structure showing

the check device thereon and in elevation;

Figure 3 is a horizontal sectional view similar to Figure 1 but showing the door and check in open position;

Figure 4 is a sectional view taken substantially upon the line 4—4 of Figure 1;

Figure 5 is a sectional view taken substantially upon the line 5—5 of Figure 4;

Figure 6 is a view in end elevation of the piston cylinder showing the pivotal support therefor.

Referring to the drawings in detail wherein like numerals of reference indicate the corresponding parts throughout the several views, the door check comprising this invention is shown as applied to a screen door 1, this door being mounted in the door frame 2 upon the hinges 3 which are preferably of the spring-controlled type which are placed under tension when the door is opened and act to force the door to closed position when it is released.

The check comprises a cylinder 4 having secured to the forward end thereof one leaf of a hinge 5 the other leaf thereof being mounted upon the inner face of the door at the top and adjacent the free forward edge thereof.

The rear end of the cylinder 4 is closed by the cap 11 and through this cap there projects a piston rod 12, the inner end of which is attached to a suitable piston 12' slidably positioned within the cylinder.

The free outer end of the piston rod 12 is pivotally connected as at 13 to one end of a check arm 14. The other end of the arm 14 is pivotally secured by a bolt 15 to the under side of the top of the door frame 2, or to a suitable carrying block or body 16 which is attached to the under face of the top of the door frame. The check arm at its inner end works through a portion of its swing when the door 1 is operated beneath a friction plate 17. The friction plate 17 is held in place by the bolt 15 and carries a forwardly extending arm 18 through which a suitable attaching screw 19 is passed. At opposite sides the plate has a portion of its edge turned upwardly as indicated at 20 and these opposite side portions are free for

movement toward or away from the body 16 so that as the check arm 14 is swung with the door to open position it slips from beneath the resilient side portions of the friction plate and when the door returns to closed position the check arm is forced beneath the resilient portion of the plate adjacent thereto and has its movement retarded thereby.

Lying beneath the friction plate 17 and the arm portion 18 thereof is a substantially triangular stop plate 21, a portion of each of two edges of which is formed to provide the flange 22 against which one side edge of the check arm 14 abuts when it is brought to door closed position.

Overlying the friction plate 17 is a friction plate spring 23 which is of substantially T-shaped configuration, each of the arms 24 thereof being turned downwardly at their ends as indicated at 25, to bear against the friction plate 17 in the manner shown, these down turned ends of the arms bearing upon the friction plate adjacent the aforementioned up turned free sides thereof. The intermediate portion 26 of the spring is traversed by the bolt 15 which holds the friction plate and check arm in position while forwardly of the holding bolt 15 the spring has passed therethrough, between the ends of the arms thereof the tensioning screws 27 which force the ends of the arms downwardly against the friction plate.

The piston cylinder 4 adjacent the forward or attached end thereof is provided with suitable air escape apertures 28 by means of which the air within the cylinder is allowed to escape slowly during the closing operation of the door thus effectively checking this operation and preventing the door from slamming. At its rear end the piston cylinder has attached to the cap an arcuate leaf spring 29 which is interposed between the cylinder and the door, but is normally out of contact therewith.

When the door 1 is swung to open position the cylinder 4 will of course be drawn outwardly therewith and will pull upon the piston rod 12 and the check arm 14. The check arm permits the door to be swung to an open position in a plane substantially parallel with the closed position of the door. When the door is released it will, of course, be swung to by the spring hinges 3 and the compression of the air in the cylinder by the piston prevents, during the first part of the movement of the door, the immediate return of the piston to the forward end of the cylinder, and the check arm is therefore moved first, being swung around against the stop 22. However, its movement just previous to its contact with the stop will be checked by the resistance offered to it as it moves under the friction plate 17. After the check arm has returned to position, or while it is returning to position, the piston

within the cylinder 4 will be slowly advancing to the forward end of the cylinder as the air therein escapes. When the door is opened to its full position the spring 29 is pressed against the door and placed under slight tension and acts when the door is released to give it an initial movement, thus assisting the spring hinges or any other spring devices which may be employed for forcing the door to closed position.

From the foregoing description it will be readily seen that the structure to which the check arm 14 is attached may be easily reversed to adapt the door check to a left hand opening door as well as a right hand opening door in which position it will act in the same manner as described in connection with the position in which it is here shown.

Having thus described my invention what I claim is:—

1. In combination in a door checking device, a piston carrying cylinder designed to be pivotally attached to a door, said piston having a connecting rod attached thereto, a check arm pivotally attached at one end to said rod and designed to have its other end attached to a fixed structure adjacent the door, and means free from engagement with the check arm when the door is open acting to receive and check the inward swinging movement of said arm as the door closes.

2. In combination in a door check structure, a piston and piston rod carrying a cylinder designed to be pivotally attached at one end to a door adjacent the free forward edge thereof, a check arm having pivotal connection at one end with said rod, means for pivotally securing the other end to a fixed structure designed to be positioned adjacent the hinged side of a door, and resilient frictional means acting upon said arm to oppose its free movement to coact with the retarding action of the piston and cylinder substantially as described.

3. In combination in a door check structure, a piston and piston rod carrying a cylinder designed to be pivotally attached at one end to a door adjacent the free forward edge thereof, a check arm having pivotal connection at one end with said rod, means for pivotally securing the other end to a fixed structure designed to be positioned adjacent the hinged side of a door, resilient frictional means acting upon said arm to oppose its free movement, to coact with the retarding action of the piston and cylinder substantially as described, and resilient means disposed between the cylinder and the door and placed under tension when the door is opened, to give an initial closing movement thereto.

4. A mounting for a check arm of a door check designed to coact with a cylinder and piston in the manner described, comprising a stop plate against which the check arm is de-

signed to abut, a friction plate secured adjacent the stop plate and designed to have the check arm move therebeneath into frictional engagement with one face thereof, and a resilient plate secured over one face of the friction plate and acting to re-enforce the friction plate in its opposition to the movement of the check arm over the face thereof, said check arm mounting being of a character to adapt it for use in connection with right or left hand opening doors.

5. In combination in a door check, a piston carrying cylinder designed to be pivotally attached to a door, said piston having a connecting rod attached thereto, a check arm having pivotal connection at one end with said rod and designed to have its other end pivotally attached to a fixed structure adjacent the door, and means arranged adjacent the pivot point of said other end of the check designed to receive the arm immediately following the closing movement of the door and previous to the movement of said piston in the cylinder to frictionally grip 20 and retard the movement of the arm.

25. 6. A mounting for a pivoted check arm of a door check of the character described, comprising a fixed plate having a stop against which the arm is designed to be brought to rest, pivot means for said arm, and a resilient friction plate overlying a portion of said arm and formed and arranged to have an increasing amount of the check arm moved therebeneath as the arm is swung in one direction about said pivot means, said pivot means securing the friction plate in position 30 over the stop plate.

35. 7. A mounting for a pivoted arm of a door check designed to coact with a cylinder and piston in the manner described, comprising a plate having a stop against which the arm is designed to be brought to rest, a pivot for one end of said arm, a resilient friction plate overlying the first mentioned plate and 40 formed and arranged to have an increasing amount of said arm moved therebeneath and in frictional contact therewith as the arm is swung in one direction about said pivot, and a resilient plate overlying the face of the 45 friction plate opposite the face engaging said arm and exerting pressure upon a portion of the same beneath which the arm moves when swinging in the said direction.

50. In testimony whereof I hereunto affix my
55 signature.

HENRY PERRY.
